WALTER M. BUCHER, OF MAR VISTA, CALIFORNIA

FLUID-POWER ROTARY DRIVE

Application filed September 25, 1929. Serial No. 395,073.

My invention is a power fluid and rotary drive which may be used for a variety of purposes and is illustrated in connection with a drive for a vehicle.

5 An object of my invention is the construction of a fluid power rotary drive in which a hydraulic fluid such as oil pumped under pressure is forced outwardly from the axis of rotation of a wheel to blades on the inside 10 of the periphery and the return flow of the fluid is from the blades to the axis of rotation.

A further object of my invention is therefore to have a complete cycle of operation 15 utilizing the hydraulic fluid over and over again and the reaction of the fluid against the blades rotates the wheel and such wheel may be used for a variety of purposes such as supporting and driving a vehicle or for transmitting power.

20 A further object of my invention is the construction of a wheel having a fixed axle housing with the wheel rotating thereon, the wheel housing having provisions for the flow of hydraulic fluid under pressure to fixed conduits, such conduits extending outwardly in the wheel towards the periphery and discharging against vanes or blades arranged internally of the periphery of the wheel. 25 The fluid after reacting on the vanes is discharged into a return passage which conducts the fluid back to the axle housing and thence again to the pump.

25 A further object of my invention is to have a movable valve in the axle housing so that on shifting of this valve the hydraulic fluid may be forced through either of two separate sets of conduits to rotate the wheel in a forward or a backward direction, or in which the valve may be turned to a neutral position allowing a by-pass flow of the fluid directly back to the pump without operating on the vanes. By this construction the wheel may be driven in opposite directions or may remain stationary.

Another object of my invention is in the handling of the fluid thrown outwardly in the vanes by a centrifugal action and causing this centrifugal action to drain the space between adjacent vanes of the fluid forced there-

in from the nozzles connected with the ducts and allow a free return of such fluid uninfluenced by centrifugal action back to the axle housing.

30 A still further object of my invention is in the provision of return passage for the hydraulic fluid, first from between the vanes, these being closed where the vanes are acted upon directly by the fluid from the nozzles and then the bucket-like spaces between the vanes opened by the rotation of the wheel to allow drainage of such buckets by centrifugal action and in connection with this construction the provision of return passages for the fluid where such fluid is not influenced 35 by centrifugal action due to rotation of the wheel.

35 Other minor features of my invention will appear from the description and claims. My invention is illustrated in the drawings, in which

40 Figure 1 is a side elevation of a partly broken away wheel in various sections, exposing the interior construction of the wheel;

45 Fig. 2 is a partial section on the line 2—2 of Fig. 1 in the direction of the arrows;

50 Fig. 3 is a vertical section substantially on the line 3—3 of Fig. 1 in the direction of the arrows;

55 Fig. 4 is a plan of the pump and control valve shifting mechanism partly broken away, taken in the general direction of the arrow 4 of Fig. 5;

60 Fig. 5 is a vertical section on the line 5—5 of Fig. 4 in the direction of the arrows.

65 In the drawings I illustrate a fixed axle housing 11. This has an angular oil retainer ring 12 mounted thereon. A fixed tube 13 is secured to the axle housing by a key 14 there being an opening 15 through the axle housing connecting with an opening 16 through the hub. These openings are on the top portion of the housing and the hub. A fixed structure 17 is carried by the hub, this having inner walls 18 and 19 which are attached to flanges 20 such flanges being integral with the hub. Outer walls 21 and 22 are connected to the inner walls by stay bolts 23 and by welded flanges 24 or the like adjacent the hub. 70 Adjacent the upper portion of the wheel the 75

inner walls 18 and 19 are provided with a rim 25 and with a cover plate 26 attached to the rim.

This cover plate has an outwardly bent rim section 27 extending partly around the wheel for a purpose hereinunder detailed; this upwardly extending portion being omitted at the parts designated 28 and 29 of the wheel. At the bottom portion of the wheel there is a plate-like rim 30 which merges into the cover plate 26 at the bottom. At the top of the wheel there are converging walls 31 which lead from substantially the line of the rim 25 to the opening 16 in the hub and 15 in the axle housing. The outer walls 21 and 22 are secured to the inner walls by stay bolts 32; some of these being connected to the rim 25 and others being connected to the cover plate 26. The outer walls each have an inwardly turned flange 33.

The rotor mounting designated generally at 34 utilizes anti-friction bearings 35 which are illustrated as having a stationary roller race 36 fitted on the axle housing, rollers 37 and a rotary race 38. The rotary wheel structure designated generally at 39 has two annular rings 40 and 41 which are parallel to the axle housing and in which the rotary races 38 fit, there being flanges 42 on the inner side. Flat rings 43 and 44 extend outwardly from the ring 41 and to these are attached inner and outer disks 45 and 46 the attachment being illustrated as by bolts 47. The rotor and its bearings are held in position on the axle housing by a nut 48 screwed on the housing and bearing against a washer 49. A cover cap 50 connects the ring 44 on the outside of the wheel and covers the open end 51 of the axle housing. There is a felt ring 52 between the inner ring 43 and the oil retaining angular ring 12.

The outer part of the rotor or wheel 53 has a rim or felloe 54 attached thereto and connecting the opposite disks 45 and 46 there are stay bolts 55 having a spacing sleeve 56. This felloe has an annular groove 57 to facilitate attaching a tire rim or the like. The vanes or blades 58 used in the propulsion of the device extend inwardly from the felloe 54. The space between two adjacent rims may be designated as a bucket 59. At the outer portion of each bucket there is a small tube 60 extending outwardly through bucket forming rings 61 which extend around the felloe on each side of the blades. These small tubes 60 have their open ends covered by the portion 27 of the blade 26 and exposed at the cut away section 28 for a purpose hereinunder detailed.

The control valve designated generally by 60 the numeral 62 has a fixed valve housing 63 secured in a fixed position in the axle housing, this having one port 64 which opens upwardly towards the opening 15 of the axle housing and has two lateral ports 65 diametrically opposed and each of these ports

communicated with a fluid conduit or duct 66, these extending in diametrically opposite directions. Each has two curved nozzle sections 67 and 68, the nozzles discharging hydraulic fluid into the buckets to strike the vanes. 70

A tubular valve stem 69 is mounted at one end in the valve housing 62, this being secured in position by a nut 70 attached to the outer part of the stem. Such stem has a port 71 which is adapted to register with either of the lateral ports 65 for driving the wheels or the by-pass port 64 which discharges into the axle housing. The space in the upper part of the wheel between the inner fixed walls 18 and 19 and the sloping walls 31 may be designated as a return fluid chamber 72. The walls 18 and 19 of this chamber are provided with outlets 73 adjacent their periphery discharging into the flat annular passage 74 between the stationary inner and outer plates 18 and 19, 21 and 22. There are also exhaust openings 75 through the flanges 20 and the inner portion of the walls 18 and 19. As the fixed structure having the walls 18 and 19, 21 and 22 is not rotatable, there is no centrifugal action on the fluid in the space 74. There are also a series of outlet openings 76 in the outer walls 21 and 22 adjacent the inner portion and these are arranged in alignment with the openings 77 in the flat ring 44 connected to the rotor disks 45 on the outside portions of the wheel. The openings 76 discharge into the annular space 78 between the outer fixed walls 21 and 22 and the rotary disks 45 and 46. 100

The pump assembly designated generally at 79, employs a pump housing 80 properly secured at a center portion of the axle housing 11, the housing therefore being stationary and having a pump casing 81 therein which pump has a rotary gear pump 82 mounted therein, there being an inlet port 83 into the sump 84 and a discharge port 85 into the central space 86. The pump is illustrated as being connected midway of the ends of the axle housing 11, it being presumed that there are two axles on this housing, both for driving the vehicle. 110

The control of the valve utilizes the rotary hollow valve stems 69, each of these being illustrated as having a head 87 in the space 86 of the pump with packing 88 and a packing gland 89 to prevent leakage. Each of the stems 69 is provided with a gear 90 which meshes with a slideable rack 91. These racks have guide rods 92 extending through guides 93 in the pump housing and lead to any suitable control. It will be seen therefore that by reciprocating the rods and hence the racks, that the hollow stems 69 may be rotated to bring their ports 71 into alignment with either of the lateral ports 65 discharging to the nozzles or to the by-pass ports 64 discharging into the axle housing. 125

In the operation of the device, presuming 130

- the hydraulic fluid from the pump is being pumped through the hollow spindles 69 and through one of the ports 65 as indicated in Fig. 1, then the hydraulic fluid follows the 5 direction of the curved nozzle and impinges on the buckets and the vanes of the buckets of the rotor of the wheel; thus giving a driving action against the vanes and rotating the wheel in the direction of the arrow 94 of such 10 Fig. 1. The main portion of the hydraulic fluid after exhausting its force driving against the vanes, flows into the chamber 72 between the inner walls 18 and 19 and the sloping walls 31 and is thence discharged into 15 the hollow axle housing and hence returns to the pump, flowing into the sump 84. In addition the hydraulic fluid may flow outwardly through the openings 75 in the inner walls 18 and 19 adjacent the hub, thence 20 through the openings 76 in the outer walls and the openings 77 in the inner part of the ring 44 with which the cover 50 is secured and hence through the open end of the axle housing to the pump. 25 Where the hydraulic fluid impinges on the vanes and buckets, the ends of the small tube 60 are closed by the portion 27 of the cover plate 26. Therefore immediately adjacent the nozzles the fluid is confined in the buckets. The centrifugal action of the rotating buckets in addition tends to force this fluid centrifugally outwardly and when the tubes 60 are successively opened when they reach the cut out section 28, the fluid therein is 35 freely discharged into the space 74 between the outer parts of the inner walls 18 and 19 and the outer walls 21 and 22 of the stator part of the machine. Thus this liquid is not subjected to a centrifugal action and flows out 40 either through the openings 76 and 77 or 75 and back to the axle housing. It is obvious that by reversing the valve action that the wheel may be driven in the opposite direction to that shown in Fig. 1 and when the fluid 45 is discharged through the ports 64, there is no driving action.

Various changes may be made in the principles of my invention without departing from the spirit thereof as set forth in the description, drawings and claims.

I claim:

1. A fluid power rotary drive comprising a stator element having fluid ducts discharging in a general upward direction, having a main fluid discharge passage and auxiliary fluid discharge passages at the sides of the main passage, a rotor having a series of buckets with vanes opening inwardly adapted to receive the fluid discharged from the ducts, the waste fluid from the buckets being in part discharged through the first passage to the main passage and means in the buckets to discharge the residual fluid into the auxiliary passages.
2. A fluid power rotary drive comprising

in combination a stator element having a central fluid supply with ducts having nozzles discharging in a general upward direction, the stator having a main return passage leading downwardly and discharging into a central 70 return passage, a rotor having a series of buckets with vanes opening inwardly and receiving fluid from the nozzles, the waste fluid from the buckets being discharged downwardly by gravity through the said passage. 75

3. A fluid power rotary drive as claimed in claim 2, the buckets having a series of openings and the stator having means to close said openings extending partly around the periphery of the stator, and return auxiliary 80 passages in the stator to receive the residual fluid discharged through the openings by centrifugal force, the said passages having connection through the central return passage.

4. A fluid power rotary drive comprising 85 in combination a hollow axle housing forming a return liquid passage, a structure having a liquid supply passage therein, a valve connected to said structure, a stator element having a plurality of ducts having nozzles 90 connected to said valve to discharge liquid in opposite directions and in a general upward direction, the stator having a main return passage converging downwardly through the sides to the axle housing, a rotor element rotatable on the axle housing and having a plurality of buckets with vanes opening inwardly, the buckets receiving the liquid discharged from the nozzles and being adapted 95 to be driven in opposite directions depending on the position of the valve. 100

5. A fluid power rotary drive as claimed in claim 4, the valve having means to discharge the supply fluid into the axle housing and giving a by-pass return to eliminate 105 the drive on the rotor.

6. A fluid power rotary drive as claimed in claim 4, the rotor having openings from the buckets on opposite sides and the stator having cover plates extending over said openings from positions in which the buckets receive the fluid from the nozzles to a discharge 110 position of the buckets and there being annular passages in the stator to receive the fluid discharged by the openings in the buckets 115 with means to conduct the fluid from said passages to the hollow axle housing.

7. A fluid power rotary drive comprising 120 in combination a single hollow stationary axle housing having an opening extending upwardly for a return liquid flow to said housing, a tubular rotatable valve stem extending through the housing and having a valve at one end, a plurality of ducts connected in a stator element attached to the 125 housing and extending laterally in opposite directions substantially horizontally, said ducts having nozzles discharging in a general upward direction, the stator having inner walls with a main discharge passage formed 130

therein converging downwardly considered in a peripheral direction to the said opening in the housing, a rotor rotating on the housing and having a plurality of buckets with vanes opening inwardly, the nozzles discharging into said vanes, means to rotate the stem to discharge fluid in either sets of ducts to rotate the rotor in opposite directions, the waste fluid from the buckets discharging downwardly through the said main discharge passage.

8. A fluid power rotary drive as claimed in claim 7, the stator having outer walls extending in a circle and forming annular passages between the outer and inner walls, said walls having openings and the rotor having outer walls with openings, a cover connected to the outer walls of the rotor on one side and bridging an opening in the end of the axle housing, the buckets having openings with means on the stator to form a closure for said openings adjacent the discharge of the nozzles, the said latter openings being opened for the major portion of a circle to discharge fluid by centrifugal force into the passages between the inner and outer walls of the stator.

9. A fluid power rotary drive comprising a stator element having means to supply power fluid and means to convey the waste fluid, a rotor element having a series of buckets opening inwardly, the supply fluid being discharged into said buckets, the main portion of the waste fluid being discharged downwardly, the buckets having openings and a stationary covering for said openings adjacent the place of discharge of the power fluid into the buckets, the said openings being uncovered for a portion of the rotation of such buckets, whereby the residual fluid may be discharged by centrifugal force.

10. A fluid power rotary drive having a stator with means to supply a power fluid having discharge nozzles and means for the return of the waste fluid and having auxiliary lateral passages for centrifugally discharged waste fluid, a rotor element having a series of buckets opening inwardly, the nozzles discharging into said buckets, the main waste supply dropping from the buckets into a main return passage, the buckets having openings, a stationary element forming a closure for the buckets adjacent the place of discharge of the nozzles, the openings being uncovered for a portion of their revolution and the residual waste fluid being adapted to discharge through the openings into lateral return passages.

11. In a fluid power rotary drive, a stator element having a pair of inner disk-like walls and a pair of outer disk-like walls, there being a space between said walls for discharge of waste fluid, ducts in the stator having discharge nozzles, a rotor element having outer disk-like walls on opposite sides and spaced

from the outer walls of the stator, a series of buckets on the rotor opening inwardly, the nozzles discharging into said buckets, the main waste from the buckets being adapted to discharge between the inner walls of the stator and waste fluid discharged by centrifugal force through openings in the bucket being adapted to discharge through passages between the inner and outer walls of the stator.

12. In a fluid power rotary drive as claimed in claim 11, the stator walls being secured at their inner portion to a hollow axle housing, said housing having a valve connected to a source of fluid supply, the valve being adapted to discharge into at least two different nozzles to rotate the rotor in opposite directions, the rotor having a rotatable mounting on the housing.

13. A fluid power rotary drive comprising a hollow axle housing, a tubular valve stem extending through said housing and having a valve at one end, means to rotate the said stem to direct the fluid in the valve in different directions, there being ducts with discharge nozzles forming part of a stator element, a rotor element rotatably mounted on the housing and having a series of buckets opening inwardly, the said nozzles being positioned to discharge into the buckets above the axle housing and the stator having a return downwardly converging passage to the axle housing for the main waste fluid from the buckets, each of the buckets having at least one opening adjacent the bottom of the bucket, a curved plate secured to the stator and forming a closure for said openings adjacent the points of discharge of the nozzles, said plate being cut away to expose the said openings during part of the rotation of the buckets and return passages in the stator to the axle housing for fluid discharged by centrifugal action from the buckets.

In testimony whereof I have signed my name to this specification.

WALTER M. BUCHER.
